US0D1103819S

(12) **United States Design Patent** (10) Patent No.: **US D1,103,819 S**
(45) Date of Patent: ** Dec. 2, 2025

(54) **NECKLACE**

(71) Applicant: **WINDMAX ELECTRONIC COMMERCE PTE. LTD.**, Singapore (SG)

(72) Inventor: **Aiman Huang**, Singapore (SG)

(**) Term: **15 Years**

(21) Appl. No.: **29/874,802**

(22) Filed: **Apr. 25, 2023**

(51) LOC (15) Cl. **11-01**

(52) U.S. Cl.

USPC **D11/11**

(58) **Field of Classification Search**
